Harry C. Mangold, Humboldt, Tenn., assignor to Wayne Knitting Mills, Humboldt, Tenn., a corporation of Indiana

Filed Nov. 2, 1961, Ser. No. 67,355

Term of patent 14 years

(Cl. D47—7)

FIG. 1 is a front elevational view of a lady's stocking, showing my new design.

FIG. 2 is an enlarged fragmentary view of the upper portion of the stocking shown in FIG. 1.

The picot band and the colored band extend completely around the stocking in the welt area, while the balance of the back is of conventional configuration. The essential feature of the design resides in the specific, downwardly pointing arrowhead, of contrasting color in the afterwelt on the front, substantially as shown.

I claim:

The ornamental design for a stocking, as shown and described.
